representation of my design.

Fig 1 being a perspective view of the Stove, standing on its legs, and mounted with an ornament, or urn, on top. Fig 2. being a view of the end. The back of the Stove corresponds exactly with the figures on the front and the two ends exactly with each other. The detail of the ornaments on all the separate plates are seen in Fig 1+2.

The figures are not easily described in words but fully represented in the drawings.

What I claim as my invention and desire to secure by Letters Patent is the combination and arrangement of ornamental figures forming respectively the outside plates of my Parlor Stove as herein represented & described.
